UNITED STATES PATENT OFFICE.

JOSEPH E. EVANS, OF BEDFORD, INDIANA, ASSIGNOR OF ONE-FOURTH TO OLIVER N. CLIFFORD, OF ST. LOUIS, MISSOURI, AND ONE-FOURTH TO JASPER O. GYGER, OF BEDFORD, INDIANA.

SUSPENSION DEVICE FOR EQUALIZING THE STRAIN ON ELEVATOR-CABLES.

1,323,357.

Specification of Letters Patent.

Patented Dec. 2, 1919.

Application filed September 7, 1916. Serial No. 118,833.

To all whom it may concern:

Be it known that I, JOSEPH E. EVANS, a citizen of the United States, residing at Bedford, in the county of Lawrence and State 5 of Indiana, have invented certain new and useful Improvements in Suspension Devices for Equalizing the Strain on Elevator-Cables, of which the following is a specification.

10 In the various widely used types of elevators or lifts in general use for conveying passengers or freight from one floor of a building to another, the car is suspended from one end of a group of cables which 15 run over a grooved pulley arranged at the top of the elevator shaft, the car being counterbalanced by weights also suspended by cables running over a pulley at the top of such shaft. The arrangement of the pulleys and method of counterbalancing the 20 car differ with different makers, but in practically all cases a group of several cables is used to sustain the car, and also the counterweight. Because of variations in the 25 manufacture of the cables they are liable to stretch more or less unequally, with the result that all of them do not at all times sustain an equal strain or load, provided they are rigidly secured to the car, or counterbalance. The principal object of my invention 30 is to provide means for equalizing the strain upon the cables so that each will carry an equal part of the load, and in case of the breaking of any one cable the weight carried by it will be equally distributed among 35 the remaining ones. I have further provided an automatic braking device which, upon the breaking of any one cable, will apply a brake to stop the car, and in carrying out my invention I have made provision 40 for making a record of the variation in strain upon the cables, whether due to the load carried by them or to variations in the speed of the car, or to a sudden application of the driving power to the cables to 45 lift the car. In one form of my device I have also made provision for cushioning the load upon the cables, whereby liability of damage from sudden changes of strain is 50 minimized.

My invention consists in the combination and organization of elements and of parts of the apparatus which I have devised for the attainment of the above mentioned ob-

jects, and in various advantageous structural features which will be apparent from the description of the device hereinafter given, as more particularly pointed out in the appended claims.

In the drawings Figure 1 represents somewhat diagrammatically one form of elevator to which my invention is applied; Fig. 2 is a side view, partly in section, showing the equalizing device alone; Fig. 3 is a section on the line 3—3 of Fig. 2; Fig. 4 is 65 a horizontal section on the line 4—4 of Fig. 2; Fig. 5 shows a pressure gage connected to the equalizing device; Fig. 6 is a side view of a modified form of my invention adapted for use with a different arrangement of cables; Fig. 7 is a top plan view of such modified form of device; and Fig. 8 is a top plan view of a hydraulic brake forming part of my device.

The same reference characters indicate 75 the same parts in all the figures of the drawings.

Describing first the preferred form of my device illustrated in Figs. 1 to 5, the cables 1 by which the car 2 is suspended extend to a loop which passes twice over the top of the suspension pulley 4 at the top of the elevator shaft and once below the idler pulley 5, arranged immediately below the suspension pulley. The suspension pulley 85 will thus be formed with twice as many grooves as the number of cables employed,—in the present instance six cables being used,—and the cables may be divided into two groups, connected respectively in a manner which will shortly be described, to two groups of equalizing pistons and cylinders, the members of each group being arranged in staggered relation to the members of the other group, as indicated in Fig. 4, so that 90 the pistons may lie in accurate alinement with the grooves of the pulley in which the cables run. As shown in Figs. 1 and 2 the two groups of pistons and cylinders are arranged or distributed in two different lateral 100 planes which are both tangential to the periphery of the suspension pulley 4 and lie equidistant on opposite sides of a direct vertical tangential plane through the periphery of such pulley.

The cables 1 are separately attached to the top members of piston-carrying frames 6, which, as stated, are arranged in two

groups of three each, each frame consisting of a pair of side members 7 attached to a top bar 8, which bar is connected to the cable, and a bottom bar 9 pivoted to the side bars 7 and connected to the lower end of the piston or plunger 10 which is associated with such frame. In the present instance, to provide the most flexible swivel joint possible, between the cable and the frame, and 5 permit any twisting movement to which the cables may be subject to take place, each cable end is secured to a bolt 11 which carries a bearing plate 12 provided with a ball race, and the top cross-bar 8 of the frame 10 has secured to it or has formed integrally with it, a corresponding bearing plate 13 formed with a registering ball race, a set of balls 14 being arranged between the bearing plates to form a ball-bearing connection. 15

20 The three pistons of each group are arranged to slide within cylinders 15 formed in a casting 16, two castings being provided, one for each group. Each casting is formed with a pair of trunnions 17 near its lower 25 end, journaled in bearings 18 secured to beams 19 which form a part of the top of the frame of the car. The castings 16 are preferably formed with vertical recesses on each side adapted to receive the side bars 7 30 of the frames 6. In the present instance, for convenience in manufacture, the cylinders are bored entirely through the castings and the tops of the bores closed by plugs 20. A cup leather gasket 21 is secured to the top 35 of each piston 10 to prevent the escape of the oil with which the cylinders are filled past the pistons, and inasmuch as the tops of the cylinders are imperforate, the oil is in this manner sealed therein with the greatest 40 possible effectiveness.

The cylinders of each casting communicate freely with each other through ports 22 at or near their tops, and a channel 23 is provided affording communication between the 45 cylinder space and a bore 24 through one of the trunnions. A section of flexible metallic hose or tubing 25, the interior of which is a continuation of the bore 24, is secured in a suitable manner to the trunnion, conveniently, as in the present instance, by a centrally perforated clamping nut 26 screwing onto a threaded neck formed on the trunnion and clamping tightly to said neck a flange 27 brazed or otherwise secured to the 50 tubing. The two sections 25 are united by a T-connection 26^a to a common flexible tube 27^a which is thus in free communication with all the cylinders. A pressure gage 28, having an indicating needle 29, playing over 55 a clock-actuated calibrated card 30 and arranged to make a record thereon, is provided to indicate and record variations of pressure in the cylinders.

It will be understood that the intercommunicating cylinders and pipe passages

leading to the pressure gage being all filled with oil, the pressure on the tops of the pistons is necessarily equal, and the stretching of any cable, or the unequal stretching of two cables, or all three of them, will result 70 simply in a compensating displacement of the oil to accommodate the stretch of the cables and the irregular, vertically-shifted position of the pistons. The strain on the cables will therefore be exactly equal, and 75 the fluctuation of fluid pressure shown by the indicator will indicate the stress on the cables, whether due to the dead-load of the car standing still or traveling at a uniform speed, or to the inertia of the car upon 80 starting, or its momentum when stopping. If any cable should break, the piston connected to it will sink to the lowermost position permitted by the construction of the parts,—but not outside its cylinder,—the 85 oil from the other cylinders flowing into the cylinder affected, and the other pistons rising correspondingly and jointly taking up the weight before carried by the broken cable. 90

In the preferred form of my invention now being described the breaking of a cable operates to cause the automatic setting of a hydraulic brake to restrain further movement of the car. To this end communicating channels 31 are formed in each cylinder body, terminating in a port 32 in each cylinder wall, arranged to be uncovered by the plunger at the extreme position occupied by it when its cable breaks. The channels 31 through a pipe 33 communicate with the brake cylinder 34 of a hydraulic brake carried by the car, the pistons 35 of which brake are coöperatively connected with brake shoes adapted to coöperate with fixed 105 ways secured at the sides of the elevator shaft. In the present instance I have illustrated a suitable connection for this purpose consisting of a double-faced cam 36 carried by the ends of the piston rods 37 each cam 110 being arranged to coöperate with the inner ends of a pair of pivoted levers 38, the outer ends of such levers being arranged, when the brake pistons are operated, to grip the opposite sides of the inwardly extending 115 flanges of vertical T-bars 39, arranged at opposite sides of the elevator shaft and serving as guides for the car. If desired, a pneumatic buffer may be provided by only partially filling the cylinders 15 with oil, 120 thus leaving an air space at the top of the cylinders to serve as air cushion.

In Figs. 6 and 7 I have illustrated a modified form of my invention which is adapted for use on elevators in which the cables are 125 spaced but a short distance apart, as in elevators in which the cables pass but once over the top of the driving pulley and lie in adjacent grooves an inch or less apart. In such a case cylinders of proper size can- 130

not be aggregated in a pair of castings, as in the form of my invention hereinbefore described, and four separate castings 40, one for each cable, and each formed with trunnions 41, are provided, the cylinders being arranged in staggered relation on the trunnions as shown, so that the pistons may lie in accurate alinement with the grooves on the pulley in which the cables run. As in the preferred form of my construction heretofore described the cylinders and pistons are distributed in different tangential planes arranged on opposite sides of a vertical tangential plane passing through the periphery 10 of the suspension pulley. In this modified form of my invention the trunnions are shown as formed with channels communicating with the cylinder spaces, and a different form of yielding connection to permit a free tilting movement of the cylinder castings on their trunnions is provided, consisting of pipes 42 secured to the trunnions and each bent into a coil 43 secured to a common pipe 44 which communicates with the pressure gage; but it will be understood that in either the preferred form of my invention hereinbefore described, or in the modified form shown in Figs. 6 and 7, any suitable flexible connection permitting flow of liquid 20 from one cylinder to another may be employed in place of the specific forms of intercommunicating channels and tubing or pipes shown and described.

Where one end of a group of cables is attached to the car and the other end to the counterweight, it is obviously possible to attach the suspension devices either to the car or the counterweight, or to attach one set to the car and another to the counterweight. Furthermore, it is obvious that while the pressure gage and the brake apparatus above described are particularly useful in elevator cars in combination with my equalizing cylinders and pistons, the latter may be used 30 alone, and will be highly valuable as a suspension device without the other parts of the apparatus, both in elevator cars and generally in other kinds of apparatus in which it may be useful to equalize the strain upon a group of cables.

I claim:

1. A suspension device for connecting an elevator car or the like to hoisting cables, comprising a plurality of pistons and a corresponding plurality of intercommunicating cylinders, one set of elements being flexibly attached to the car and the other connected to the cables and said elements being distributed in different lateral planes tangential to the suspension pulley.

2. A suspension device for connecting an elevator car or the like to hoisting cables, comprising a plurality of pistons and a corresponding plurality of intercommunicating cylinders, said cylinders being pivotally at-

tached to the car and said pistons being connected to the cables and said elements being distributed in different lateral planes tangential to the suspension pulley.

3. A suspension device for connecting an elevator car or the like to hoisting cables comprising a plurality of pistons, a corresponding plurality of intercommunicating cylinders, said cylinders being secured to the car and having closed upper ends and said pistons being connected adjacent their lower ends to the cables.

4. A suspension device for connecting an elevator car or the like to hoisting cables, comprising a plurality of pistons, a corresponding plurality of intercommunicating cylinders, said cylinders having closed upper ends and being pivotally attached to the car, and said pistons being connected adjacent their lower ends to the cables, and having their upper ends equipped with gaskets.

5. A suspension device for connecting an elevator car or the like to hoisting cables, comprising a plurality of pistons and a corresponding plurality of intercommunicating cylinders, said cylinders being pivotally attached adjacent their lower ends to the car and said pistons being connected adjacent their lower ends to the cables and said elements being distributed in different lateral planes tangential to the suspension pulley.

6. A suspension device for connecting an elevator car or the like to hoisting cables including a plurality of pistons and a corresponding plurality of intercommunicating cylinders, said elements being arranged in two groups in staggered relation and one set of elements being secured to the car and the other set to the cables.

7. A suspension device for connecting an elevator car or the like to hoisting cables, comprising a plurality of frames swiveled to said cables, a corresponding plurality of pistons pivotally mounted on said frames, and a corresponding plurality of intercommunicating cylinders pivotally attached to the car.

8. A suspension device for connecting an elevator car or the like to hoisting cables, including a plurality of pistons connected respectively to said cables, a cylinder body formed with trunnions pivotally secured to said car, and with intercommunicating cylinders corresponding to said pistons.

9. A suspension device for connecting an elevator car or the like to hoisting cables, comprising a plurality of pistons connected respectively to said cables, two cylinder bodies each formed with trunnions and cylinders, and all the cylinders in both bodies being arranged in communication with each other, said pistons being disposed in the cylinders of the two cylinder bodies in two groups.

10. A suspension device for connecting an elevator car or the like to hoisting cables, comprising a plurality of pistons connected respectively to said cables, two cylinder bodies each formed with trunnions and intercommunicating cylinders, said cylinder bodies and trunnions being formed with channels communicating with the cylinders, and a flexible pipe connection communicating with the channels in both cylinder bodies, said pistons being disposed in the cylinders of the two cylinder bodies in two groups. 55
11. A suspension device for connecting an elevator car or the like to hoisting cables, comprising a plurality of frames secured to said cables, a corresponding plurality of pistons pivotally mounted on said frames, two cylinder bodies pivotally connected with said car and each formed with intercommunicating cylinders, all the cylinders in both bodies being arranged to communicate with each other, said pistons being disposed in the cylinders of the two cylinder bodies in two groups. 60
12. The combination of a suspension device for connecting an elevator car or the like to hoisting cables comprising a plurality of pistons and a corresponding plurality of intercommunicating liquid-filled cylinders, one set of elements being secured to the car and the other set to the cables, and a hydraulic brake apparatus including a brake cylinder arranged to be placed in communication with any one of said liquid-filled cylinders upon excessive movement of the piston in said cylinder. 65
13. The combination of a suspension device for connecting an elevator car or the like to hoisting cables comprising a plurality of pistons and a corresponding plurality of intercommunicating liquid-filled cylinders, one set of elements being secured to the car and the other set to the cables, and a hydraulic brake apparatus connected in common to said liquid-filled cylinders and arranged to brake the car upon excessive movement of any piston. 70
14. The combination of a suspension device for connecting an elevator car or the like to hoisting cables comprising a plurality of pistons and a corresponding plurality of intercommunicating liquid-filled cylinders, one set of elements being secured to the car and the other set to the cables, and a hydraulic brake apparatus co-operatively related to all of said pistons and arranged to brake the car upon excessive movement of any piston. 75
15. The combination of a suspension device for connecting an elevator car or the like to hoisting cables comprising a plurality of pistons and a corresponding plurality of intercommunicating liquid-filled cylinders, said cylinders being pivotally attached to the car and said pistons being connected to the cables, and a hydraulic brake apparatus including a brake cylinder, said first-mentioned cylinders being each formed with a port uncovered by the piston in said cylinder upon excessive movement of each piston and there being a channel connecting said port and said brake cylinder. 80
16. The combination of a suspension device for connecting an elevator car or the like to hoisting cables comprising a plurality of pistons connected respectively to the cables and cylinder bodies formed with cylinders and having trunnions pivotally secured to said car, there being a cylinder for each piston and the cylinders all communicating with each other and each cylinder being formed with a port uncovered by its piston upon excessive movement of such piston and one trunnion of each cylinder body being formed with a channel in communication with each cylinder port therein, and a hydraulic brake apparatus including a brake cylinder in common communication with the channels in the trunnions of the cylinder bodies. 85
17. The combination of a suspension device for connecting an elevator car or the like to hoisting cables comprising a plurality of pistons and a corresponding plurality of intercommunicating liquid-filled cylinders, one set of elements being secured to the car and the other set to the cables, a hydraulic brake apparatus including a brake cylinder, each of said pistons being arranged to govern communication between its liquid-filled cylinder and said brake cylinder, and a pressure gage in communication with the body of liquid in the cylinders. 90
